WITNESSES

United States Patent Office.

MONTRAVILLE BUFFUM, OF LEOMINSTER, MASSACHUSETTS.

Design No. 3,975, dated April 19, 1870.

DESIGN FOR A WATCH-CHAIN.

The Schedule referred to in these Letters Patent and making part of the same

I, MONTRAVILLE BUFFUM, of Leominster, in the State of Massachusetts, have invented a new and original Design for Watch-Chains, of which the following is a specification.

It consists, as shown in the accompanying drawing to which reference is made, in a series of long bars of uniform section, to be made of some positively-colored non-metallic substance, such as rubber, horn, pearl, ivory, shell, or hoof, linked together by bright metallic links of gold, gilt, or silver, two of which pass

through the ends of the bars, and the third, an elliptical link doubled on itself, unites the others.

I claim as my invention—

The design for a watch-chain, substantially as described and shown.

M. BUFFUM.
